APPARATUS FOR DIE PRESSING METAL PLATES

John P. Gallagher, Jersey City, N. J., assignor, by mesne assignments, to Standard Railway Equipment Manufacturing Company, a corporation of Delaware

Application April 5, 1938, Serial No. 200,141

2 Claims. (Cl. 113—49)

The invention relates in general to a method for die pressing metal plates into corrugations, embossments and the like, and to a form of die structure designed for use in practicing the method.

The present invention was developed incidental to the perfecting of the method for forming pressed steel car ends of the type disclosed in my Patent No. 2,004,199, June 11, 1935, wherein it is suggested that internally reinforced, integral steel panels may be formed by inserting red hot steel stock plates between forming dies of the requisite contour and the resulting panel formed conventionally as the two dies are brought towards each other under pressure with the hot plate therebetween.

The primary object of the present invention is to form a beamed panel of the type disclosed in my above identified patent by a judicious redistribution of the available metal in the stock plate to avoid abnormal thinning out of the material which forms the walls and thus to dispose or rather retain as much metal as possible in the walls which form the beams and add to the same from the immediately surrounding areas.

The present disclosure features a peculiar form of coacting dies which are so formed that just before the final stages of the pressing operation they lock the metal outlining each of the segregated areas from further creeping movement across the locking lines and thus confine the metal available during the final wall forming step to that which is locked within the outlines of its associated segregated area.

A further object of the invention is to cause the metal as it forms each wall to have an initial, relatively unrestricted freedom of slippage or stretch at its opposite long edged portions. It is a particularly novel feature of this disclosure that the degree of permissible slippage or stretch at opposite edges of the forming wall is not the same but is controlled to regulate the amount of material drawn into the walls from the two regions beyond the side edges of the walls.

Considered in another way, while it is an objective of this disclosure to provide a technique for forming panels which will have approximately uniformity in thickness of material in all portions thereof, it is more important to control the thickness of material in the die pressed portions so that certain selected areas shall have a slightly greater thickness than certain other selected areas.

Another object of the invention is to provide an improved technique and a simple form of

means for minimizing this escape of heat by conduction from portions of the hot plate during the period of time after the hot plate is located in position and during the succeeding initial step of the die forming operation.

Accordingly another object of the invention is to provide a die pressing in which the resulting panel may be formed in one die pressing operation and will be free of internal strains in the marginal portions and thus to maintain the outlining marginal portions in their initial flat condition and free of puckering or wavy areas.

Another object of the invention is to provide for a die structure from which the formed panels may be withdrawn without distortion.

Various other objects and advantages of the invention will be in part obvious from a consideration of the method features of the disclosure and from an inspection of the accompanying drawings and in part will be more fully set forth in the following particular description of the method of practicing the invention, and the invention also consists in certain new and novel modifications of the preferred method and other features of construction and combination of parts hereinafter set forth and claimed.

In the drawings:

Fig. 1 is a plan view of a finished panel constituting the lower of a two panel car end produced by a method utilizing either one of the three die forms herein featured;

Fig. 2 is an enlarged sectional view taken on the line 2—2 of Fig. 1;

Figs. 3, 4, 6, 7 and 8 illustrate one form of dies for forming the panel of Fig. 1 and which form will be referred to sometimes hereinafter as the first embodiment or modification;

Fig. 3 is a plan view looking upwardly onto the underside of the upper die element of Figs. 6—8;

Fig. 4 is a view looking downwardly onto the top of the lower die element of Figs. 6—8;

Fig. 5 is a plan view of an unembossed stock blank with its corners cut out before it is fed to the die press and which blank is shown in dotted line position resting on the lower die element in Fig. 4 and in full lines in Figs. 12, 13, 16 and 20;

Figs. 6, 7 and 8 are each vertical, longitudinal sectional views through the coacting die elements taken on the lines 6—6 of Figs. 3 and 4 showing the two outer end parts of the complete die, that is, the part outside of the dot and dash lines 6—8 of Figs. 1, 3 and 4, and in the succeeding views reading upwardly of the sheet showing the dies

in succeeding stages of their die pressing operations following the initial flanging operation;

5 Figs. 9, 10 and 11 correspond respectively to the showings in Figs. 6, 7 and 8 and disclose a slightly modified form of die elements hereinafter sometimes referred to as the second embodiment or modification and illustrated means for practicing a slightly different method of procedure in forming the corner post car end flanges;

10 Figs. 12 and 13 are each vertical sectional views corresponding to a part of the left hand end of either Figs. 6, 9, or the corresponding portion of the die in Figs. 16-19 showing two modified forms of the initial contacting elements 15 of the die structure and also showing in the stippled areas of the hot plates regions of relatively lower temperatures at the initial stages of the pressing operation;

15 Figs. 14 to 20 inclusive disclose a later design 20 constituting another and commercially perfected physical embodiment of the invention sometimes hereinafter referred to as the third embodiment or modification in which:

25 Fig. 14 is a plan view of the lower or male die somewhat corresponding to the showing in Fig. 4;

Fig. 15 is an inverted plan view of the upper or female die somewhat corresponding to the showing in Fig. 3;

30 Figs. 16, 17, 18 and 19 are each longitudinal sectional views with the upper elements taken on the line 16-16 of Fig. 14 and with the lower elements taken on the line 17-17 of Fig. 15 showing succeeding steps in the panel forming 35 operation and wherein:

Fig. 16 shows the position of the dies spaced apart with the blank corresponding to that shown in Fig. 5 but of larger dimension inserted in place ready to be depressed;

40 Fig. 17 shows the position with the locking flanges bent and the upper die just coming in contact with the blank;

Fig. 18 shows the dies in their final pressing position;

45 Fig. 19 shows the dies restored to their open position and the finished pressing lifted up from the lower or male die;

Fig. 20 is a transverse sectional view taken on the line 20-20 of Fig. 16; and on 20-20 of Figs. 50 14 and 15; and

Fig. 21 is a descriptive detail view showing in light lines a plan of one of the triangles of Fig. 1 when constructed on the third modified form of dies as hereinafter described.

55 The showing in Fig. 1 in its disclosure of triangular or X-forms of interconnected embossments is copied from Fig. 1 of my above identified Patent No. 2,004,199, except that the panel extends horizontally, and the showings of the 60 completely formed panel of Figs. 11 and 19 are each a section on the line 11-11 of Fig. 1 and corresponds substantially to the showing in Fig. 6 of my patent, the several parts being similarly numbered.

65 Referring to the drawings of the die parts and particularly to Figs. 6 to 8, there is shown a die press 10 represented by the upper die holder 11 to which is demountably secured the depending upper die element 12, sometimes hereinafter referred to as a female die, and a lower die holder 13 carrying on its upper side the lower die element 14 sometimes hereinafter referred to as a male die. In the showing in both the Figs. 6-8 and in the Figs. 9-11 form, the upper die element is of slightly larger dimensions con-

sidered horizontally than the lower die element similarly measured and is designed to telescope onto the same as the elements nest one into the other. As will be noted later the parts which form the corrugations and embossments in the final panel are reversed, that is, the interior work engaging area of the upper die element of Fig. 6 corresponds to the interior work engaging area of the lower die element of Fig. 9 and the other companion die elements in the two forms are similarly reversed. The die elements of both forms are of conventional rigid metal construction, preferably semi-steel, arranged in relatively superposed order and each provided with complementary channels and troughs, projections and depressions necessary to die press the stock material, work or sheet to the desired configurations disclosed in the finished panel of Fig. 1. The undersurface of the upper die element 12 and the upper surface 20 of the lower die element 14 in Figs. 3, 4, and 8 to 11, each constitute a work engaging or forming surface of undulatory form as shown in the several sectional figures and of an open lattice work form as shown in plan in Figs. 3 and 4. The die face of the upper die element 12 as shown in Figs. 3 and 8 is formed of a set of ribs 15 connected end to end, having substantially flat or slightly concaved crown faces and inclined side walls 16 conforming in plan outline and opposing their associated channels 17 in the other die element 14 and which channels have flat bottoms 18 and slightly inclined side walls 19. The ribs and channels coact to form the interconnected, long, somewhat flat-top corrugations 31-34, 35 and 36 in the finished panel (Fig. 1). The element 12 is also provided with a pair of frusto-conical bosses 21 coacting with similarly shaped depressions or cavities 22 in the element 14 to form the bull's eye or embossments shown 40 at 42 in Figs. 1 and 8. The depressions 22 likewise are outlined by inclined side walls 19 and a flat bottom 18.

The channels 17 as they are arranged at the edges of the element 14 coact to form triangular 45 shaped projections 23 which coact with the similarly shaped recesses 24 in element 12 to form the single triangular areas 40 in the original plane of the finished plate. The X-arrangement of the channels 17 in the interior part of 50 the element 14 form between them the four sides and rounded corner square, doughnut-like projections 25 which coact with the similarly shaped recesses 26 in the element 12 to form the double triangular areas 39 in the finished 55 panel.

One of the distinctively novel features of this disclosure is that the crown portions of the ribs 15, sometimes called major projections, are not perfectly flat but are provided with shallow longitudinally extending air-gap forming recesses 27, distinct from the die forming surfaces, so as to form on opposite sides thereof a pair of long, parallel, spaced apart, narrow-width contact strips 28 and 29, hereinafter sometimes called 60 minor projections, which do form part of the die forming surfaces.

The elevated portion 25 surrounding the cavity 22 in Fig. 4 is outlined by a recess defined on its inner perimeter by a circular contact rib 70 37 and on its outer perimeter by a rectangular, rounded corner endless contact rib 38, designed to form the parts which first come in contact with the hot plate after the initial flange bending operation hereinafter described. Similarly 75

the boss 21 (Fig. 3) is provided centrally of its crown portion with a flat circular recess 41 encircled by an annular ring-like contact rib 43. The high portions forming the work engaging surface of the lower die element provide a plurality of work supporting narrow lines sufficient in area and disposition to support the hot stock plate of Fig. 5 against sagging when positioned thereon after being flanged and preparatory to being die pressed.

It will be understood as by reference to Fig. 6 that in the old method and assuming that the insulating recesses herein featured, such as the shallow recesses, were omitted, the hot plate when positioned on top of the lower die element lost its heat rapidly over the entire area in engagement with the lower die as indicated by the width $a-b$ as shown at the right of Fig. 6, that is, there would be a heat loss over the entire upwardly presented annular area between the circular depression and the depressed straight and diagonal depressions or channels. Similarly, if the recesses 27 in the upper die were omitted, heat would be extracted from their corresponding area as soon as this advance portion of the upper die contacted with the upper side of the hot plate. However, as shown in Fig. 6, the several heat insulating recesses in each case reduce the area of contact from the width $a-b$ as shown by example at the right side of Fig. 6 by the amount $c-d$ thus leaving unavoidable heat leakage areas, but areas which are relatively narrow, as indicated by the stippled areas.

In the case of the Figs. 6-8 disclosure it is intended, as the first step in the die press operation, to bend the blank along the score lines indicated in Fig. 5 to form four long narrow outlining marginal extensions 46, 47, 48 and 49 marked in this order clockwise on Fig. 5, and shaped to form locking flanges for securing the blank in the die during the die-pressing operation herein featured. The opposite shorter extensions 47 and 49 become in the Fig. 11 disclosure the car end side post or attaching flanges, the right flange being similarly numbered 47 in the finished end of the panel in Fig. 2.

Each edge of the upper die element in both forms of the same is provided with an extension 53, L-shaped in cross section, projecting integrally from each of the four edges of the interior or stock pressing area of the die element. The L-extension forms, in effect, a depending, continuous, four-sided shoulder or frame 54 and an endless four-sided channel 55 into which is pressed the flanges 46-49, and the portion of the stock plate immediately adjacent these flanges as shown in Figs. 6-8, by the engagement therewith of a four-sided rim 56 outlining the lower die element 14. The lower die element has an all-over horizontal dimension less than the distances between the opposing shoulders 54 so as to accommodate therebetween in rather snug relation the thickness of material which forms the locking flanges 46-49 when bent from their initially flat position shown in Fig. 5 into the locked position held between the die elements as shown in Fig. 6. It is suggested that the location of the inner face of the shoulders 54 be defined by a replaceable wear plate 57 which may be of variable thickness and that the inner work engaging faces 58 of the wear plates be accurately located to compensate for variations in thickness of the work stock by the use of one or more thin shims 59 located between the wear plates and the shoulders. Similarly the

adjacent lower outer four edges of the lower die 14 may each be cut back to form a shouldered recess 60 in which is replaceably mounted a coacting wear plate 61 backed by one or more thin shims. The wear plates 57 and 61 are referred to sometimes hereinafter as a flange bending means.

In order to prevent the outlining panel from freezing to the die, the peripheral wall such as is shown at 67 in Fig. 9 may be inclined or a space may be left between engaging parts, such as between the wear plates 57, 61 in Fig. 6.

It is noted in the form of die elements herein selected for description of the invention that the ridges over which the metal is drawn during the pressing operation, such as the strips 28 and 29 in Fig. 8, are substantially semicircular in cross section with a relatively short radius. In other words, when it is desired to have areas of relatively large thickness of material on one side of this ridge in the final panel, the metal is caused to pass over portions of small curvature because these sharply contoured bends offer relatively greater resistance to the creeping or stretching of the metal across the same from one to the other side than would be the case if the radius of curvature were larger. In other words, in those areas where it is desired to keep the thickness on one side of the ridge almost that of the original thickness of the blank 45, such areas are surrounded or at least partly outlined by more or less sharp ridges which at least tend to obstruct the free movement of the metal across the same.

As a contrary instance, it will be noted that the circular contact rib 37 and the four-sided rib 38 (see Fig. 9) are also substantially semi-circular in cross section but in this case each has a relatively long radius. In this case the metal is met with less resistance to creeping or stretching over the ridges of this long radius contact strip than in the situation above as hereinafter more fully described.

It is another distinctive feature of the die construction that the die elements do not bottom to provide for variation in plate thickness and for the accumulation of dirt and scale.

Figs. 12 and 13 show multiple part die elements intended to provide a construction at the crown portion of the ribs to minimize heat losses into the die elements.

In the showing in Fig. 13, the supplemental part 88 may be of the same material as the main part or it may be of a different material as discussed with reference to the showing in Fig. 12. In the Fig. 13 modification, the supplemental and main parts are separated by a layer 81 of insulating material, such as asbestos, which acts to retard heat transference from the supplemental parts 77 to the main part 78 of the die. In this case the work engaging surface is formed partly on the main part 78 and partly on the supplemental part 88 and extends continuously from one to the other across the joints formed by the layer of insulating material 81.

In operation and referring first to the disclosure in Fig. 6, it will be understood that with the die elements conventionally separated, the hot plate in the flat form shown in Fig. 5 is withdrawn from the heating furnace and as quickly as possible located in position on the lower die as indicated by the dotted lines in Fig. 4 following conventional practices in this respect. As quickly as practicable the upper die is lowered, or the lower die is raised, usually by pneumatic,

hydraulic, or mechanical pressure onto the hot plate first to engage the extensions 46-49 which project beyond the outlines of the lower die element, to bend the extensions at right angles to the body of the blank, to form the bent locking flanges 46-49 into the form shown in Fig. 6, that is, by bending the four edges of the blank of Fig. 5 from the dotted line position into the full line position of Fig. 6. Then with the continued lowering of the upper die element the blank passes through the Fig. 7 stage into the Fig. 8 stage and the corrugations and embossments are thus formed as is usual in such die forming operations on heavy steel plates. It is an important feature of this disclosure that the locking flanges be formed before the dies begin to form the several corrugations and embossments which give design to the finished panel and the stage in the operation where the die elements have just locked the flanged but unembossed plate in position as shown in Figs. 6 and 9.

It will be understood that while the metal in the outstanding flat marginal edges of a blank plate could not be held from creeping inwardly into the blank interior when simply held between the jaws of a clamping device; in this case the bent flanges, extending as they do more or less at right angles to the plane of the balance of the plate being die-pressed, acts to clamp the plate in the direction of its plane and the plate is held even under conditions where the clamping effect is of a relatively low order as in the case of the Figs. 6-8 disclosure. In the method herein disclosed the blank is held rigidly at its outlining edges and all of the stretch in the material necessary to form the corrugations takes place in spaced relation to the outlining edge of the blank and as a result no wrinkling or puckering occurs at the edges of the finished panel. By eliminating the drawing of the plate internal stresses are prevented along the rails and edges of the panels.

It is understood that this discussion relates to relative temperatures and it is within the scope of the disclosure to perform the pressing operation with hot dies. As a matter of fact, it is practically impossible to keep the dies from heating during the course of rapidly repeated pressing operations and it is therefore to be assumed in this description that the dies are not at room temperature but are operating at the high temperatures usual in work of this character. Every effort is made to maintain the dies at the same temperature and thus avoid variations in the dimensions of succeeding pressings. This disclosure is simply featuring the minimizing of areas of contact between the hot plates and the portions of the dies, both lower and upper, which engage the plate during the initial stages of the pressing operation after bending the locking flanges.

Considering the situation during the Fig. 7 step of the first form and which likewise applies to the situation during the Fig. 10 step of the second form, the parts 39 and 40 which form the flats as well as the marginal strip 83 are in the original plane of the stock plate. Referring specifically to the part bridged across the channel 17 at the left of the figure and which eventually forms the corrugation 33, it will be noted that the metal forming the right wall 113 for instance, overlaps the ridge 38 of relatively large diameter and underlaps the ridge 29 of relatively small diameter. At this time the metal necessary to form wall 113 is being stretched from

both the areas 40 and 33 but not at the same rate. As noted above, the large radius 38 offers relatively little resistance to the escape of metal from the area 40 and the small radius 29 is offering relatively greater resistance to the escape of metal from the area 33. Therefore, at this time the stretch is momentarily more from the area 40 than from the area 33 and thus metal is taken out of the flat 40 more rapidly than it is taken out of the part which eventually will form the crown of the corrugation 33. As the dies move from the Fig. 7 showing towards the Fig. 8 showing the metal has progressively more difficulty in rounding the short radius ridge 29 and eventually the fold of the metal about this relatively sharp ridge becomes so pronounced that it will no longer stretch or creep and the metal is locked along the line at 29. During this time the forming wall 113 continues to draw the metal from the area 40 with progressively increasing resistance until just before the dies reach the Fig. 8 position when the metal is locked along the crown of the large radius ridge 38. This means that material is drawn into the wall 113 from the area 40 practically up to the termination of the pressing operation with, of course, reduction of thickness of material in the flat 40.

After both long edges at 29 and 38 of the wall 113 lock as thus described, the dies move into their final nested position as shown in Fig. 8 and at that time the wall 113 is completely formed with perhaps a slight final stretch and thus a slight reduction in what otherwise would have been its thickness.

Following the method herein of utilizing the form of recess topped die element herein featured, these abnormally thinned out areas are not present in the finally completed panel and in this way lines and regions of weakness characterizing such panels as heretofore constructed have been eliminated. In the completed panel as constructed as herein suggested, it has its marginal portion 20 slightly reduced from its initial thickness especially along the edge nearest the corrugations 31 and 32, thus retaining in the edge portion, that is, the uncorrugated outlining portion of the panel, the structural strength necessary to form the riveted lap joint structures disclosed in the above identified pressed steel car end patent. However, the portions including the outlining frame 31, 32, 33 and 34, and the corrugated and embossed areas enclosed therein have substantially the same thickness throughout all portions thereof, but, of course, this interior thickness is reduced from the thickness of the original plate and reduced from the thickness of the marginal portions 20.

With the form of heat insulating crown portion disclosed in Fig. 13, the operation is as above described except that, as the rate of discharge of the heat from the hot plate to the crown portions of the ribs or projections over the entire crown area is less than in the case of the steel dies in the Figs. 3 and 4 form, the rate of heat discharged has been minimized and to this extent the escape of heat across the points or lines of contact has been retarded. It is also noted, especially in the case of the Fig. 12 disclosure, that the amount of material in the supplemental parts 77 may be reduced in volume for the purpose of minimizing the heat capacity of the crown portions. It would follow therefore in the Fig. 12 form of the disclosure that the mass of material in the supplemental part 80 being com-

paratively small compared to the entire die would quickly reach a temperature approximating that of the hot plate being acted upon and thus reduce the rate of heat transference between the 5 hot plate and the hot crown portions. Fig. 21 shows diagrammatically the method of preventing undue stretching of the sheet. The triangular area 40 may correspond to the area 40 of Fig. 1. The wall 113 at an edge of the 10 triangle is formed at an angle of 120°. At a 90° corner, such as 116, the slope is made flatter in order to prevent drawing too much metal from the walls 114, 115 with consequent excessive thinning thereof. At sharper corners, such as 121 15 which is 45°, the wall is still flatter, being 138° as compared with 130° for a 90°. It is to be understood that the angles mentioned are intended as examples only and not as a limit upon the invention.

20 Figs. 14 and 16 to 20 show an arrangement for elevating the panel from the lower die immediately upon raising the upper die at the completion of the pressing operation, thereby minimizing the danger of uneven cooling on opposite sides of the panel with consequent shrinkage strains. Two spaced apart plungers 124 rest upon a beam 125 which in turn is supported by the piston 126 of a pneumatic cylinder 127. Movement of the piston 126 raises the panel 25 30 from the lower die, the upper ends of the plungers being relatively small to prevent heat transfer.

Figs. 14, 15 and 20 show a die adapted to form a pressed panel with a flat area adjacent thereto. A one-piece center die 93 is encircled by a

rail of which the extension member 105 is a part. Ribs and embossements which have been heretofore described are formed by the center die 93 while the flat area 128 is formed between the center die 93 and extension member 105. The 5 flat area may comprise, for example, the end plate of a railway car.

I claim:

1. In a die press for forming corrugations in a metallic plate comprising reciprocating upper and 10 lower dies, each of said dies being provided with a plurality of parallel ribs so positioned that the ribs of one die move between the ribs of the other die upon reciprocation of the dies, the crown portion of each of said ribs being provided with a 15 recess to reduce area of contact between said plate and said ribs, said dies being provided with means to form flanges on the margins of the plate upon reciprocation thereof before the ribs of one die move between the ribs of the other 20 die for securing the metallic plate in the dies during the formation of the corrugations.

2. In a die press for forming corrugations in a metallic plate comprising reciprocating upper and lower dies, each of said dies being provided 25 with a plurality of spaced apart ribs so positioned that the ribs of one die move between the ribs of the other die upon reciprocation of said dies so that said metallic plate upon being inserted between said dies is pressed during said reciprocation, the crown portions of said ribs having rounded edges, said edges having different radii of curvature so that the plate slides over some of the edges less rapidly than over the other edges. 30

JOHN P. GALLAGHER. 35
